UNITED STATES PATENT OFFICE

2,685,967

MAGNETIC ORE SEPARATOR

James H. Johnstone, Biggs, Calif.

Application May 25, 1953, Serial No. 357,221

1 Claim. (Cl. 209—219)

1

The present invention relates to a magnetic separating apparatus that is designed to separate non-magnetic ore bearing materials from magnetic ore bearing materials and is more particularly constructed to provide a magnetic ore separator for separating the rare metals such as gold and platinum and the like from granular material containing both magnetic and non-magnetic ores.

At present, in working rare metal bearing ore beach sands, the sands continually shift and no economically efficient ore separation apparatus is available which is portable, whereby it can be moved from place to place in accordance with the shifting sands.

Accordingly, the primary object of the present invention is to provide a magnetic ore separator of light weight and separable construction which is easily transported and set up for operation.

Another very important object of the present invention is to provide a magnetic ore separator wherein a unique magnetic pulley is provided which utilizes permanent magnets necessitating no electrical connections and substantially reducing the weight of the pulley over any comparable prior art device.

A still further object of the invention is the provision of a magnetic ore separating apparatus, including a main supporting frame and an auxiliary frame carrying the magnetic pulley which is removably and adjustably mounted on the main supporting frame whereby the tension, elevation and length of the runs on the separator conveyor belt may be varied to meet the needs and desires of the operator of the apparatus.

These, together with various ancillary objects and features which will later become apparent as the following description proceeds, are attained by the present invention, a preferred embodiment of which is shown by way of example only in the accompanying drawings wherein:

Figure 1 is a top elevational view of the magnetic separator constituting the present invention;

Figure 2 is a side elevational view of the invention with parts being shown in cross section for clarity of detail;

Figure 3 is a sectional view of the invention taken substantially along the plane of section line 3—3 of Figure 2;

Figure 4 is a cross sectional view of the magnetic pulley of the present invention taken substantially along section line 4—4 of Figure 1; and

Figure 5 is a cross sectional view of the pulley 55 auxiliary frame 36 are spaced apart from one

2

taken substantially along section line 5—5 of Figure 4.

Referring now to the accompanying drawings in detail wherein like reference numerals are utilized to designate similar parts throughout the various views, the magnetic separating apparatus constituting the present invention is designated in its entirety by the numeral 10.

The apparatus is of extremely light weight construction and is designed primarily for following rich ore veins which are not permanent enough or present in a sufficient amount to warrant the construction of a permanent separating plant for their processing from the beach sands.

Referring more particularly to Figures 1-3 of the drawings, the construction of the separating apparatus will be most clearly observed. The apparatus comprises generally a main frame 12 of substantially rectangular configuration and including legs 14 and 16 at the ends thereof respectively. The legs 14 and 16 are arranged in pairs with each pair of legs being connected at their upper ends to one another by the cross beams or braces 18 and 20 and at their lower ends by the cross braces 22 and 24 respectively. Thus, each end section constitutes a rectangular frame as designated by the legs 14, and cross beams 18 and 22 or their opposite end members designated by the numerals 16, 20 and 24.

30 Mounted on top of the ends of the sections and extending therebetween are a pair of parallel, longitudinally extending beams 26 which form the top of the main supporting frame 12. As will be noted particularly from Figures 2 and 3, the beams 26 are mounted on top of the cross braces 18 and 20 of the end sections whereby they in effect form guide tracks for a purpose that will subsequently appear.

40 The forward ends 28 of the beam extend beyond the cross beam 18 and have transversely aligned bearings or pillow blocks 30 mounted thereon. A drive shaft 32 is journaled in the bearings 30 and is connected at one end to a suitable power source (not shown). Centrally 45 on the drive shaft 32 is secured a drive pulley 34.

Removably mounted between the longitudinal beams 26 is an auxiliary frame designated in its entirety by the numeral 36. The auxiliary frame constitutes a pair of transversely spaced, parallel, longitudinally extending main frame members 38 interconnected at their ends to one another by cross frame members 40 and 42 respectively.

The side or main frame members 38 of the auxiliary frame 36 are spaced apart from one

another a distance less than the longitudinal beams 26 are spaced apart from one another so that the auxiliary frame 36 may slide between the longitudinal beams 26. Intermediate the ends of the side frame member 38 are mounted bearing blocks 44 within which the ends of driven shaft 46 extending between the members 38 are journaled. Centrally on the driven shaft 46 is mounted the magnetic pulley 48. Additional bearing blocks 50 are mounted adjacent the forward ends of the frame members 38 and idler shaft 52 extending between the members 38 has its ends journaled in the bearing blocks 50. Idler pulley 54 is mounted on the idler shaft 52.

As will be noted from the drawings, the rearward end of the auxiliary frame 36 rests directly upon the cross beam 20. The forward end of the frame 26 includes a supporting bar or strap 56 which is secured to the cross member 42 by means of the vertically projecting fastener 58. The ends of the bar 56 rest on the top of the beams 26 to support the front end of the auxiliary frame 36 on the supporting frame 12. By suitably adjusting the fastener 58, the forward end of the frame 36 may be raised and lowered.

At the rearward ends, the side frame members 38 of the auxiliary frame 36 are provided with downturned end flanges 60. Adjusting screws 62 extend through these end flanges 60 and abut the cross beam 20 whereby the auxiliary frame 36 may be moved forward and rearwardly.

Endless conveyor belt 64 is entrained over the pulleys 32, 36 and 54. The length and elevation of the upper rung of the belt 64 may be controlled by suitable adjustment on the fasteners 58 and 62 on the auxiliary frame 36.

The magnetic pulley 48 is comprised essentially of a pair of semi-circular sections 66 of non-magnetic material joined to one another by suitable fastening means 68 as shown in Figure 4 to form a wheel. Discs 70 having a radius somewhat greater than the radius of the wheel formed by the sections 66 are provided as side plates whereby a circumferential channel is provided around the rim of the wheel. A plurality of permanent block magnets 72 are disposed within the channel in circumferentially spaced relation to one another. The magnets 72 are retained in such relation by a suitable plastic filler such as plaster of Paris or the like. A band of aluminum 76 or other suitable non-magnetic material forms a cover for the channel and encloses the magnets 72 within the magnetic pulley 48. It is understood that the materials utilized in the construction of the magnetic pulley are all non-magnetic with the exception of the permanent block magnets 72.

Thus, the driven pulley 48 provides a magnetic wheel or pulley which requires no external energy

to maintain its magnetic field or wires or commutators subject to wear and deterioration.

When the machine or apparatus 10 is in operation, a suitable sand dispensing hopper 78 is mounted adjacent the forward end of the main frame 12 to dispense the ore bearing sand onto the upper rung of the conveyor belt 64 between the drive pulley 34 and the magnetic driven pulley 48. As the sand passes over the driven pulley 48, the rear metal bearing portions of the sand will not be affected by the magnetic field set up by the magnetic pulley 48 and will fall into a suitable receptacle 82 as that portion of the conveyor belt 64 passes the point at which a freely falling body would be released therefrom. The magnetic ore bearing particles, however, are retained on the conveyor belt by the action of the magnetic field until that portion of the conveyor belt passes completely through the magnetic field upon which event, the magnetic tailings are gathered in a separate receptacle 84.

From the foregoing description, the construction and operation of the invention will be readily apparent. However, since numerous modifications and changes will readily occur to those skilled in the art after a careful perusal of the foregoing specification taken in conjunction with the accompanying drawings, it is not desired to limit the invention to the exact construction shown and described. But, all suitable modifications may be resorted to which fall within the scope of the appended claim.

What is claimed as new is as follows:

In a magnetic ore separator, a portable frame adapted to be mounted on a main supporting frame, said portable frame comprising a pair of side frame members connected at their ends by front and rear cross members, a magnetic pulley journaled on said frame intermediate the ends thereof, a vertically projecting threaded fastener secured to the central portion of said front cross member, and an elongated bar adjustably secured to said fastener said bar having its ends projecting beyond said side frame members to rest upon the supporting frame, said magnetic pulley including permanent magnets spaced circumferentially about the periphery of said pulley.
